UNITED STATES PATENT OFFICE

2,011,022

SPEED CONTROL MEANS FOR SPINNING MACHINES

George R. Townsend, Schenectady, N. Y., assignor to General Electric Company, a corporation of New York

Application April 6, 1935, Serial No. 15,144

13 Claims. (CL 118—32)

My invention relates to speed-controlling means for ring spinning machines and the like, more particularly to means for automatically varying the speed of the spinning machine while maintaining constant tension in the yarn during the winding operation, and has for an object the provision of simple and reliable means for varying the speed to give a high operating efficiency.

It will be understood that in filling-wind operations to which my invention relates in particular, the yarn is wound on the spindle in conical layers. At the beginning of the winding operation, a conical base is built up on the lower end of the spindle, the layers being thereafter conical for the completion of the winding operation. It will be apparent that in carrying out this winding operation, the yarn is wound on portions of the bobbin of a continually varying diameter, and it is an inherent characteristic of ring spinning machines that the tension on the yarn varies inversely with the diameter of the portion of the bobbin on which the thread is being wound, assuming a constant speed for the spindle.

In order to obtain the highest permissible operating speeds while keeping the tension on the yarn substantially constant, it is desirable that at the beginning of the winding operation, the driving motor should be running at a reduced speed, for example, 70% full speed. This speed should slightly increase as the ring rail advances along the spindle and should decrease as the ring rail returns. During the time in which the base is being built up, which generally takes approximately 40 minutes, the amplitude of this change in speed should be gradually increased and at the same time, the base speed should be gradually increased until at the time the base is completed, the speed is varying between, for example, 100% speed and 80% speed. The remainder of the bobbin is now built up by winding conical layers on the spindle, and the speed change obtained at the end of the base-forming operation should be maintained during the remainder of the winding operation. It is a further object of my invention to provide improved automatic speed-varying means for carrying out the above cycle of speed changes.

In carrying out my invention in one form, I provide a control arm or member mounted for movement on a fixed support and operatively connected to a speed varying device. Mounted on an element of the spinning machine oscillating in accordance with the relative oscillatory movement between the ring rail and the spindle, I provide mechanism for operating the control

member as the machine element oscillates, and means are provided driven in accordance with the progressive relative movement between the ring rail and the spindle for driving the operating mechanism to vary the effect of the mechanism on the control member. More specifically, I provide a plurality of cam means carried by the oscillating element of the spinning machine. One of these cam means comprises a pivoted cam lever arranged to engage a portion of a control arm supported adjacent the oscillating element and operatively connected to a speed-varying device. Another of the cam means is driven in accordance with the progressive relative movement between the ring rail and the spindle and is arranged to move the cam lever about its pivot, to vary the effect of the cam lever on the control arm as the winding operation proceeds. The cam lever is provided with a curved working surface normally concentric with the path of movement of the oscillating element so that the cam lever normally moves along the control arm without affecting movement thereof. As the winding operation proceeds, however, the cam lever is moved about its pivot by the other cam means to operate the control arm so as gradually to increase both the base speed of the machine and the amplitude of speed change which occurs during each oscillation. After a predetermined portion of the winding operation has been completed, the base speed and the amplitude of speed change are maintained constant throughout the remainder of the winding operation. Means are also provided for adjusting the cooperating relation of the cam lever and the control arm so as to vary the movement imparted to the control arm by the two cam means during the winding operation.

For a more complete understanding of my invention, reference should now be had to the drawing in which Fig. 1 shows speed control means embodying my invention applied to a typical ring spinning machine, and Fig. 2 shows a modified form of speed-control means embodying my invention applied to a different type of spinning machine.

Referring now to Fig. 1, for purposes of clarity, only the essential elements of the spinning machine directly cooperating with the speed-varying means are shown. In this particular machine, the spindle 10 is fixed in position, while the ring rail 11 is oscillated relative to the spindle as the winding operation proceeds. Obviously, however, the ring rail may be stationary and the spindle given a corresponding movement.

In order to simplify the drawing as much as possible, I have shown the ring rail in a conventional manner as being operated through a lever 12 pivoted at 13, one end of the lever being connected to the lower end of a rod 14 the upper end of which is secured to the ring rail. The other end of the lever 12 carries a weight 15 for raising the ring rail, and the lever 12 is operated against the force exerted by the weight 15 by means of a flexible cable 16, one end of which is attached to a segmental arm 17 on the lever 12.

As shown, the builder mechanism for oscillating the ring rail 11 relative to the spindle 10 comprises a builder lever 18 pivoted at 19 and having an extending pin or roller 20 arranged to be engaged by a builder cam 21. A suitable weight 22 serves to maintain the roller 20 in contact with the working surface of the cam 21. It will be understood, of course, that the builder cam 21 as well as the spindle 10 are arranged to be rotated by suitable driving connections (not shown) connecting them respectively to an electric motor 23 which forms the driving means for the entire spinning machine.

The cable 16 for operating the ring rail 11 is connected, as shown, to one end of the builder lever 18, and it will be apparent that as the builder lever is oscillated by the cam 21, the ring rail 11 will be oscillated relative to the spindle 10. In order progressively to advance the ring rail along the spindle 10 as the winding operation proceeds, one end of the cable 16 is secured to a drum 24 mounted on a shaft 25 which is driven by a gear 26. This gear 26 is in turn driven by a worm 27 mounted on a shaft 28, to the end of which is secured a ratchet wheel 29. Arranged to cooperate with this ratchet wheel is a fixed pawl 30 so positioned that as the end of the builder lever is raised, the ratchet wheel will be turned by engagement with the pawl 30 so as to rotate the drum 24 in a counterclockwise direction, thereby lengthening the cable 16 and raising the ring rail.

It will be apparent now that the builder lever 18 constitutes an element of the machine oscillating in accordance with the relative oscillatory movement between the ring rail and the spindle, and that the shaft 25 constitutes an element driven in accordance with the progressive relative movement between the ring rail and the spindle. It will be understood that the mechanism thus far described is old in the art and is shown for the purpose of a clearer understanding of the invention.

While any suitable variable-speed driving motor 23 may be used in accordance with my invention, a three-phase, slip-ring induction motor is shown. The speed of this motor is controlled by means of a rheostat 31 shown as having three resistances 32, 33, and 34 connected respectively in the rotor circuits of the motor and being variable by means of a rotatable contact device 35 having three arms cooperating respectively with the resistances. As shown, the contact member 35 is normally biased by means of a spring 36 to a position in which all of each of the resistances 32, 33, and 34 is respectively connected in the rotor circuits, and the contact member 35 is adapted to be operated from the position in a clockwise direction, as viewed in the drawing, by an operating member 37, the other end of which is connected to a pivoted control arm 38. The operating member 37 is shown for purposes of illustration as a flexible cable, but it will be obvious of course that a chain, a

cord or a rigid rod may be substituted therefor.

The control arm 38 is pivoted, as shown, on a fixed pin 39 carried by a supporting member 40 which may constitute a portion of the machine frame. Pivotally mounted on the builder lever 18 is a cam lever 41, the pivot point of the cam lever being arranged in substantially coaxial relation with the pivot pin 39 when the builder lever is in the position shown in the drawing. Adjustably mounted in a slot 42 in the control arm 38, is a pin or roller 43 arranged to be engaged by a curved working surface 44 formed on the cam lever 41. Both the slot 42 and the cam surface 44 are formed with a curvature which, when the cam 41 and the control arm 38 are in the position shown, is substantially concentric with the path of movement of the builder lever 18 about its pivot 19. In other words, each point on the cam surface 44 is radially equidistant from the pivot pin 19.

Also pivoted on the builder lever 18 is a bell crank lever 45, one end of which is provided with a pin 46 for engaging a portion 47 of the cam lever 41. As shown, the other end of the bell crank lever 45 is provided with a pin 48 arranged to be engaged by a rotatable cam 49 secured to the shaft 25.

It is believed that a complete understanding of my invention may now be had from a description of the operation. In the drawing, the apparatus is shown in a position corresponding to the beginning of a winding operation, and it will be assumed that the position of the contact member 35 is such as to insert sufficient resistance in the rotor circuits to cause the motor to operate at the desired minimum speed. When the motor 23 is energized by closing suitable control switches (not shown), the cam 21 will begin to rotate, and the right-hand end of the builder lever 18 will be raised, causing the ring rail 11 to move upwardly along the spindle. It will be remembered that the cam surface 44 on the cam lever 41 is concentric with the path of movement of the builder lever 18 and accordingly, the cam will move along the roller 43 without moving the control arm 38 in either direction. Accordingly, the speed of the motor will remain constant during the first layer of the winding operation. When the builder lever 18 reaches the uppermost point of its travel, the ratchet wheel 29 will be engaged by the pawl 30 and the rotatable cam 49 will thereupon be rotated slightly in a counterclockwise direction. This movement of the cam 49 will cause the pin 48 on the bell crank lever 45 to ride up the cam surface 50, and the consequent rotation of the bell crank lever 45 about its pivot will be effective to move the cam lever 41 in a clockwise direction about its pivot.

It will be apparent that when the cam lever 41 is rotated about its pivot, the cam surface 44 will no longer be in concentric relation with the path of movement of the builder lever 18. The control arm 38 will be moved slightly in a clockwise direction by the rotation of the cam lever 41 so as to decrease the portions of the resistances 32, 33 and 34 connected in the rotor circuit and the base speed will thereupon be slightly increased. As the ring rail and builder lever oscillate, the control arm 38 will be moved back and forth due to the non-concentric relation of the cam surface 44, causing the speed to vary from the new base speed, a maximum speed being obtained when the builder lever is in the position shown. With each oscillation of the builder lever, the cam 49 will be further rotated so as to move

the bell crank lever 45 and the cam lever 41 about their respective pivots and thereby increase the variation of the cam lever 41 from its concentric relation.

5 As the winding operation proceeds and the cam 49 is rotated, the pin 48 moves up the cam surface 50 until it passes over the shoulder between the cam surface 50 and a cam surface 51. This point of the winding operation corresponds to the completion of the formation of the base of the bobbin indicated by the reference numeral 52. During the remainder of the winding operation in which the portion 53 of the bobbin is wound, both the base speed and the amplitude of speed change during each oscillation of the builder lever and the ring rail should remain constant and accordingly, the cam surface 51 takes the form of a circle having the shaft 25 as a center. The speed of rotation of the cam 49 is such that the cam will make approximately $\frac{3}{4}$ of a complete revolution during the winding operation.

If it is desired to form a tip on the bobbin, the speed change which is obtained during the formation of the base 52 should be reversed, i. e., the base speed and the amplitude of speed change should gradually be reduced until at the completion of the tip, the speed is rotating at the minimum base speed with no speed change. This speed variation may be obtained by providing the cam 49 with a portion 54, the shape of which corresponds to the portion 50.

In some cases it may be desirable to adjust the speed variations obtained during the winding operation. This may be accomplished by adjusting the pin 43 along the slot 42. The adjusting action may best be understood by assuming that the cam lever 41 has been rotated by the cam 49 so as to exert a camming action on the control arm 38. As shown, the slot 42 is given a curvature concentric with the cam surface 44, and it will be apparent that when the builder lever is in its lower position in which the respective pivot points of the cam lever 41 and the control arm 38 are in coaxial relation, the pin 43 may be moved along the slot 42 without changing the effect of the cam surface 44 on the control arm. However, when the builder lever 18 is in its upper position, it will be apparent that the pivot points of the cam lever 41 and the control arm 38 are no longer in coaxial relation. The cam surface 44 and the slot 42 are therefore no longer concentric and if the pin 43 is now moved upwardly in the slot 42, the control arm 38 will be moved in a clockwise direction to move the contact member 35 in a corresponding direction, and cut resistance out of the motor circuit. It will be remembered that the upper and lower positions of the builder lever correspond respectively to the conditions of minimum and maximum speed obtained during each oscillation, and since adjustment of the pin 43 varies the effect of the cam 41 on the control arm 38 in the upper position without varying the cam effect in the lower position, it will be apparent that an adjustment of the speed change during each oscillation is obtained.

In Fig. 2, I have shown a slightly modified form of speed-changing means embodying my invention applied to a ring spinning machine having a somewhat different type of builder mechanism. The builder mechanism here shown comprises a builder lever 55 pivoted on a pin 56 and provided with a roller 57 positioned for engagement by a builder cam 58. A cable 59, which corresponds

to the cable 16 of the apparatus shown in Fig. 1, is connected to the end of a lever 60 also pivoted on the pin 56 and provided with a concave surface 61 which is engaged by a stud 62 on a segmental rack bar 63. As shown, the rack bar 63 is slideable in segmental guide ways 64 on the builder lever 55, and is moved and positioned by a worm 65. The worm 65 is mounted on a worm shaft 66 having a ratchet wheel 67 arranged to be intermittently advanced by a fixed pawl 68 in a manner similar to the advancement of the ratchet 29 by the pawl 30 in the mechanism shown in Fig. 1.

As the rack bar 63 is moved to the right as viewed in the drawing by the worm 65, the stud 62 moves along the concave surface 61, and the lever 60 moves upward relative to the builder lever 55, whereby the ring rail of the machine which it is understood, is controlled by the cable 59 will be progressively raised as the winding of the bobbin proceeds.

As applied to this type of spinning machine, my speed-control means comprises a control arm 69 pivoted on a pin 70 which is supported by a fixed member 71 comprising a portion of the machine frame, a cable 72 which controls a suitable rheostat in the same manner as the cable 37 in the apparatus shown in Fig. 1, and which is secured to the free end of the control arm. Pivoted on an extending arm 73 of the builder lever 55 is a cam lever 74, the pivot point 30 of which is in substantially coaxial relation with the pivot pin 70 when the builder lever is in its lower position shown, the cam surface 75, when the cam lever 74 is in the position shown, being concentric with the path of movement of the builder lever. As shown, the control arm 69 is provided with a pin or roller 76 which is adjustable along a slot 77. Pivoted on a pin 78 carried by the builder lever 55, is a second cam lever 79 having a portion 80 arranged to engage a portion 81 of the cam lever 74, another portion of the cam lever 79 being provided with suitable cam surfaces 82 and 83 arranged to be engaged by the stud 62.

It will be apparent that when the segmental rack 63 is moved to the right, the stud 62 will engage the cam surface 82 to rotate the cam lever 79 in a counterclockwise direction about its pivot 78 and thereby rotate the cam lever 74 in a counterclockwise direction about its pivot. It will be understood that the cam surfaces 82 and 83 are given a configuration such as to produce the same movement of the cam lever 74 as was imparted to the cam lever 41 by the rotatable cam 49 in the mechanism shown in Fig. 1. Inasmuch as the operation of the control means shown in Fig. 2 corresponds throughout the winding operation to the operation of the control means shown in Fig. 1, the only change being that the rotatable cam 49 and the bell crank lever 45 of Fig. 1 are replaced by the pivoted cam lever 79 in Fig. 2, it is believed that a complete understanding of the operation of the mechanism shown in Fig. 2 may be had without describing this operation in detail.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

What I claim as new and desire to secure by Letters Patent of the United States is:

1. Apparatus for controlling the speed of a ring

- spinning machine or the like, comprising means for varying the speed of the machine, a control member mounted for movement on a stationary support, an operating connection between said speed varying means and said member, mechanism mounted on an element of the machine oscillating in accordance with the relative oscillatory movement between the ring rail and the spindle for operating said control member, and means driven in accordance with the progressive relative movement between the ring rail and the spindle for driving said mechanism to vary the effect of said mechanism on said control member.
2. Apparatus for controlling the speed of a ring spinning machine or the like, comprising means for varying the speed of the machine, a control arm, an operating connection between said speed-varying means and said control arm, a plurality of cam means mounted on and bodily movable with an element of the machine oscillating in accordance with the relative oscillatory movement between the ring rail and the spindle, one of said cam means comprising a pivoted cam lever having a face engageable with a portion of said control arm to move said control arm and operate said speed-varying means as said machine element oscillates, another one of said cam means being arranged to move said cam lever about its pivot to vary the movement imparted to said control arm, said second cam means being driven in accordance with the progressive relative movement between the ring rail and the spindle.
3. Apparatus for controlling the speed of a ring spinning machine or the like, comprising means for varying the speed of the machine, a control arm, an operating connection between said speed-varying means and said control arm, a cam lever pivotally mounted on an element of the machine oscillating in accordance with the relative oscillatory movement between the ring rail and the spindle, said cam lever having a portion engageable with a portion of the control arm and normally positioned to impart zero movement thereto as said machine element oscillates, and cam means driven in accordance with the progressive relative movement between the ring rail and the spindle for moving said cam lever about its pivot, whereby said cam lever moves said control arm to operate said speed-varying means as said machine element oscillates.
4. Apparatus for controlling the speed of a ring spinning machine or the like, comprising means for varying the speed of the machine, a control arm, an operating connection between said speed-varying means and said control arm, a cam lever pivotally mounted on an element of the machine oscillating in accordance with the relatively oscillatory movement between the ring rail and the spindle, said cam lever having a face engageable with a portion of said control arm and normally positioned to impart zero movement thereto as said machine element oscillates, and cam means driven in accordance with the progressive relative movement between the ring rail and the spindle for moving said cam lever about its pivot, whereby said cam lever moves said control arm to operate said speed-varying means as said machine element oscillates, said cam means being proportioned so as to increase both the base speed and the amplitude of speed change of the machine during the winding of a predetermined portion of the bobbin after which said cam means maintains said base speed and said amplitude substantially uniform.
5. Apparatus for controlling the speed of a ring

- spinning machine or the like, comprising means for varying the speed of the machine, a pivoted control arm, an operating connection between said speed-varying means and a movable portion of said control arm, a cam lever pivoted on an element of the machine oscillating in accordance with the relatively oscillatory movement between the ring rail and the spindle, the respective pivot points of said control arm and said cam lever being substantially coaxial when said machine element is in one of two extreme positions, said cam lever having a portion normally disposed to engage a portion of said control arm without operating said control arm about its pivot as said machine element oscillates, and cam means driven in accordance with the progressive relative movement between the ring rail and the spindle for moving said cam lever about its pivot, whereby said cam lever operates said control arm about its pivot as the machine element oscillates.
6. Apparatus for controlling the speed of a ring spinning machine or the like, comprising means for varying the speed of the machine, a pivoted control arm, an operating connection between said speed-varying means and a movable portion of said control arm, a cam lever pivoted on an element of the machine oscillating in accordance with the relatively oscillatory movement between the ring rail and the spindle, the respective pivot points of said control arm and said cam lever being substantially coaxial when said machine element is in one of two extreme positions, said cam lever having a portion normally disposed to engage a portion of said control arm without operating said control arm about its pivot as said machine element oscillates, and cam means driven in accordance with the progressive relative movement between the ring rail and the spindle for moving said cam lever about its pivot, whereby said cam lever operates said control arm about its pivot as the machine element oscillates, said cam means having a portion for moving said cam lever to increase both the base speed and the amplitude of speed change for each oscillation of said machine element during the winding of the base of the bobbin, after which said cam means maintains said base speed and said amplitude substantially constant.
7. Apparatus for controlling the speed of a ring spinning machine or the like, comprising means for varying the speed of the machine, a pivoted control arm, an operating connection between said speed-varying means and a movable portion of said control arm, a cam lever pivoted on an element of the machine oscillating in accordance with the relatively oscillatory movement between the ring rail and the spindle, the respective pivot points of said control arm and said cam lever being substantially coaxial when said machine element is in one of two extreme positions, said cam lever and said control arm having co-operating portions one of which comprises a curved surface concentric with the path of movement of said machine element and the other of which comprises a pin adjustably carried in a slot having a similar curvature, said cam lever being normally positioned so that said pin moves along said curved surface as said machine element oscillates without operating said control arm about its pivot, cam means driven in accordance with the progressive relative movement between the ring rail and the spindle for moving said cam lever about its pivot, whereby said curved surface and said pin co-operate to operate said control arm and said speed-varying means as said machine element oscillates.

8. In a ring spinning machine, in combination, a driving motor, a speed-controlling device for said motor, a control arm operatively connected to said device, a builder lever, cam means pivotally mounted on said builder lever and having an operating portion all points of which are normally radially equidistant from the pivot point of said builder lever, said operating portion being normally engaged by a portion of said control arm, 5 other cam means driven in accordance with the progressive relative movement between the ring rail and the spindle for moving said first cam means about its pivot whereby said first cam means is effective to operate said control arm to vary the speed of said motor as said builder lever is oscillated.
9. In a ring spinning machine, in combination, a driving motor, a speed-controlling device for said motor, a control arm operatively connected to said device, a builder lever, a pivoted cam lever carried by said builder lever having an operating portion the surface of which is normally concentric with the path of movement of the builder lever about its pivot, said operating portion being 10 engaged by a portion of said control arm, cam means driven in accordance with the progressive relative movement between the ring rail and the spindle for moving said cam lever about its pivot whereby said operating portion is moved out of 15 said concentric relation and operates said control arm as said builder lever oscillates.
10. In a ring spinning machine, in combination, a driving motor, a speed-controlling device for said motor, a control arm operatively connected to said device, a builder lever, a pivoted cam lever carried by said builder lever having an operating portion the surface of which is normally concentric with the path of movement of the builder lever about its pivot, said operating portion being 20 engaged by a portion of said control arm, cam means driven in accordance with the progressive relative movement between the ring rail and the spindle for moving said cam lever about its pivot whereby said operating portion is moved out of 25 said concentric relation and operates said control arm as said builder lever oscillates.
11. In a ring spinning machine, in combination, a driving motor, a speed-controlling device for said motor, a control member mounted for movement on a stationary support, an operating connection between said speed-varying means and said member, mechanism mounted on an element of the machine oscillating in accordance with the relative oscillatory movement between the ring rail and the spindle for operating said control member, and means mounted on said machine element and driven in accordance with the progressive relative movement between the ring rail and the spindle for varying the effect of said mechanism on said speed-varying means.
12. In a ring spinning machine, in combination, a driving motor, a speed-controlling device for 25 said motor, a control member operatively connected to said device, a builder lever, mechanism mounted on and oscillatable with said builder lever for operating said control member, and means driven in accordance with the progressive relative movement between the ring rail and the spindle for driving said mechanism to vary the effect of said mechanism on said control member.
13. In a ring spinning machine, in combination, a driving motor, a speed-controlling device for 30 said motor, a control member operatively connected to said device, a builder lever, mechanism mounted on and oscillatable with said builder lever for operating said control member, and means driven in accordance with the progressive relative movement between the ring rail and the spindle for driving said mechanism to vary the effect of said mechanism on said control member.

GEORGE R. TOWNSEND. 50
